UNITED STATES PATENT OFFICE.

TAYLOR W. HEINTZELMAN, OF SACRAMENTO, CALIFORNIA.

LOCOMOTIVE ASH-PAN.

SPECIFICATION forming part of Letters Patent No. 634,728, dated October 10, 1899.

Application filed June 7, 1899. Serial No. 719,680. (No model.)

To all whom it may concern:

Be it known that I, TAYLOR W. HEINTZELMAN, of Sacramento, in the county of Sacramento and State of California, have invented 5 a certain new and useful Improvement in Locomotive Ash-Pans, of which improvement the following is a specification.

My invention more particularly relates to ash-pans formed in two or more comparatively deep sections, such as are employed on locomotive-engines having one or more of their axles located beneath the fire-box.

The object of my invention is to provide a locomotive ash-pan having means for admitting and regulating the supply of air to the grate which shall be readily and effectively operative by the fireman while the engine is running and which shall be exempt from liability to permit the dropping of hot coals 20 or cinders upon the right of way or bridges on the line.

To this end my invention, generally stated, consists in the combination of an ash-pan body formed of one or more open-topped sections, each having a lower discharge-opening, valve-seats, each having one or more air-supply openings and fixed to the sides of the body, air-valves controlling the openings of the valve-seats, and means for simultaneously 30 actuating the air-valves.

The improvement claimed is hereinafter fully set forth.

In the accompanying drawings, Figure 1 is a side view in elevation of a locomotive ash-pan, illustrating an application of my invention; Fig. 2, a partial plan or top view of the same, the upper portion being broken away at the right-hand end of the figure to show the construction more clearly; Fig. 3, an end 40 view as seen from the rear; and Fig. 4, a central section, on an enlarged scale, through one of the air-valves and its seat.

My invention is herein shown as applied in connection with a locomotive ash-pan of the construction for which Letters Patent of the United States No. 620,707 were granted and issued to me under date of March 7, 1899; but it is not limited in application to that or any other specific form of locomotive ash-pan. The 45 body of the ash-pan is, as in said Letters Patent, shown in the form of three connected hopper-sections 1 1 1, each of which is open

at its top to receive solid matter which may be dropped from a fire-box, below which the ash-pan is located in the usual manner and is 55 downwardly and inwardly tapered toward a discharge-opening 2 at its lower end, around which is secured a guide-frame 3, in which a discharge-slide 6, which governs the discharge-opening, is fitted to traverse. The 60 ash-pan is secured to the top rails of the engine-frame 14 or may be supported in any other suitable and preferred manner.

In the practice of my present invention an air-supply opening 23 or a plurality of said 65 openings are formed in the sides of the hopper-sections 1 of the ash-pan, and the opening or openings on each side are surrounded by a valve-seat 24, riveted or bolted to the side plate and having openings registering with 70 the air-supply openings. An air-valve 25 is fitted to traverse over and control each opening or set of openings, and the several air-valves on each side of the ash-pan are coupled one to the other by links or connecting- 75 rods 26, so as to be movable coincidently to wholly or partially cover or uncover the air-supply openings, as may be desired. The connecting-rods of the two sides are coupled at their ends by a cross-bar 27, to which any 80 suitable mechanism for actuating the air-valves from a conveniently-accessible point, preferably the foot-plate of the engine, is connected. In the instance exemplified opening and closing movement is coincidently im- 85 parted to the entire set of air-valves by means of a fluid-pressure cylinder 28, provided with a suitably-packed piston, the rod 29 of which is connected to the cross-bar 27. Air under pressure or steam is admitted to and ex- 90 hausted from the opposite ends of the cylinder 28 through pipes 30 31, controlled by a suitable four-way operating cock or valve 32, which is preferably located in the cab of the engine, so that the air-valves may be con- 95 veniently opened or closed by the fireman, as may from time to time be desired, while the engine is running.

The air-valves 25 are herein shown as of the oscillatory type, each valve controlling a 100 set of four air-supply openings and being journaled on a pivot 33, secured in a central hub or boss in the valve-seat 24 and provided with a crank-arm 34, to which the connecting-

rod 26 is coupled. It will, however, be obvious that they may, without departure from my invention, be fitted to reciprocate on the valve-seats instead of oscillating thereon, and in ash-pans employed with comparatively deep fire-boxes reciprocating valves may be found necessary to afford proper and sufficient area for the admission of air. To guard against liability to setting fire to bridges or combustible material on or adjoining the right of way by the escape of live coals or cinders from the ash-pan, the air-supply openings are covered by fire-guards formed of sheets of wire-netting or perforated plate 35, which may be secured in position by the bolts or rivets which connect the valve-seats to the ash-pan.

My invention has been found of substantial advantage in practice in affording an easy and perfect regulation of the supply of air to locomotive-grates under the different conditions of service in and between the working of the engines on heavy mountain grades when loaded to their full tonnage rating and

when descending grades or when the engine is running shut off.

I claim as my invention and desire to secure by Letters Patent—

1. In a locomotive ash-pan, the combination of a body formed of one or more open-topped sections, having inwardly-inclined side walls with air-supply openings therein, perforated fire-guards in said openings, and air-valves controlling the passage of air therethrough.

2. In a locomotive ash-pan, the combination of a body formed of one or more open-topped sections, having inwardly-inclined side walls with air-supply openings therein, perforated fire-guards in said openings, air-valves controlling the passage of air therethrough, and mechanism operative from the foot-plate of the engine for actuating said valves.

TAYLOR W. HEINTZELMAN.
